UNITED STATES PATENT OFFICE

ALBERT KARL GOTTHELF HINGST, OF VENLO, NETHERLANDS, ASSIGNOR TO FRANS VAN DER GRINTEN, OF VENLO, NETHERLANDS

APPARATUS FOR APPLYING THIN EVEN LAYERS OF LIQUIDS ON SURFACES

Application filed April 20, 1929, Serial No. 356,779, and in the Netherlands December 8, 1928.

- In the developing of modern photo-types (e. g. diazotypes), a thin layer of a liquid developer, e. g. a solution of an alkali, a solution of alkali and an azodyestuff component, or a neutral solution of an azodyestuff component, either mixed or not, with salts, buffer salts, anti-yellowing means, means for gluing etc., is often and very profitably spread in a thin even layer over the entire surface. 55
- With this process it is of great importance, that the layer should be even and exceedingly thin, and that it should be applied without rubbing. It is also important, that the developer should come only on the side 60 of the print to be developed and not on the other side. Apparatus which effect this with a certain degree of perfection are known, (see Van der Grinten et al., No. 299,042, filed August 11, 1928).
- Such apparatus are, however, rather complicated and expensive and, because for instance the work is done with two rollers, pressing on each other, they have the drawback, that pleats or other imperfections are 65 sometimes formed. Also, the developer at the beginning of the sheet to be developed comes in contact with the back.
- All these drawbacks are practically entirely removed by the use of an exceedingly simple and cheap apparatus. 70
- The proper working of this small apparatus is based on the fact, that an exceedingly thin and even layer of liquid can be put on by means of a single roller, and therefore entirely without pressure. 75
- The sheet of paper or other material to be developed passes in the apparatus in such manner that it is laid against the roller by a comb or a similar non-rotating device which acts on the back of the paper or other material. 80
- The material to be developed follows the roller over a part, for example $\frac{1}{8}$ to $\frac{1}{20}$ of its circumference, whereas on leaving the roller surface a very thin and perfectly even layer of liquid remains on the material, without formation of drops or strips of liquid on the paper or other material. It is remarkable that in the relatively short time of contact 85
- the liquid is taken up so well by the surface to be developed and this without any pressure being exerted on it for the comb exerts pressure only where its teeth rest, but not in the interstices, and yet the paper is evenly moistened. The pressure of the comb is only to effect the laying on of the paper against the roller and should be sufficient only for that purpose. It naturally goes without saying, that this surface must also co-operate, in so far that it may not push off the liquid through being too slippery or too hard or too hardly sized or by entire lack of sucking power; the liquid itself must also be taken up more or less easily. The liquid for instance must not have too high a viscosity. 90
- It seems that the capillary forces are so large, that they effect all that was supposed to have to take place mechanically in the older apparatus.
- The nature of the roller surface plays a large part. The roller is preferably chosen of moderately hard material. Yet a metal roller covered with a thin layer of soft rubber, works much better than a hard metal surface or ebonite or glass. The surface must also preferably be rough and not slippery. It should not be greasy. 95
- A long-used surface of thin soft rubber on a hard supporting roller can profitably be made rough again, for example by a treatment with fine emery-paper. The circumference and diameter of the roller also influences the result.
- Preferably thin rollers are used of about 3-4 cm. diameter. This is of special importance with thin, slack sheets. With thick coarse material the roller may have a larger diameter. The diameter of the roller may for instance be so regulated, that it works well for a certain use within certain limits for thin as well as for thick material. 100
- With phototype papers these limits are 40-150 g. per m² and therefore a roller of 3-4 cm. diameter can be used very well.
- The apparatus consists, therefore, in principle, of one roller only, running in a trough, and a comb which rests on it. Instead of a comb having its teeth spaced about $\frac{1}{2}$ to 2 cm. from each other and made of any suitable material, an equivalent device may be

used which, without being rotated, lays the material to be developed against the roller without imposing substantial pressure. A simple device for taking the paper from the roller may also be supplied, for example in the form of a comb with a distance between its teeth of 5-10 cm.; the teeth being as thin as possible. When leaving the roller the paper should be touched as little as possible on its printed side until it is dry, because otherwise stripes will be formed. It is practicable to connect the trough with a reservoir containing the developing liquid in such a manner that the level in the trough is automatically kept constant, the connection, for example, being based on the well-known principle of the bottle of Mariotte.

The apparatus is illustrated in the accompanying drawing, in which Figure 1 is a diagrammatic side view, partly in section, and Fig. 2 is a front view.

In the drawing letter *a* is the roller, *b* the paper, *c* is a celluloid comb, which is brought into and out of contact with the paper on the roller by rods *e*, pivoting on an axle *d*. The weight of the comb should be sufficient to exert enough pressure to insure the proper laying of the paper against the roller. *f* is a table over which the paper is conducted, *g* is a device to take off the paper from the roller, which may for example be a celluloid comb, which prevents the paper being carried around the roller.

h is the trough in which the roller *a* turns and which is filled with the developing liquid, the surface of which is kept on a determined level because the trough is connected by an opened cock *k*, with a closed flask *l*. When the developing liquid is used up, the cock *k* is closed, the flask *l* opened, refilled, closed and placed in its original position, after which the cock is opened.

Any known drying device of approved type can be combined with the apparatus.

By the use of a small table etc., before and behind the roller, efficient working is promoted. When using thin limp sheets, the sheet is preferably put across a stationary roller and a short distance over the take-off device. To this end, the supplying comb is made so that it can be tipped up. After putting in the sheet, the comb is tipped down and the apparatus is set in motion in one of the abovementioned ways.

By this method thin, limp sheets are prevented from adhering and going round with the rollers and underneath the take-off device. A small slip of the beginning of the sheet (which remains undeveloped) is then sacrificed. The quantity of liquid which is put on, depends on the speed of the apparatus. If this is small, then the quantity is little, in other words, the layer is thin. If the speed is high, then the quantity of liquid is large, in other words, the layer is thick. It

is, however, always uniform, except with very high speed. Speeds of $\frac{1}{2}$ to 6 meters per minute (circumference speed of the roller) can certainly be used.

The apparatus are made in widths (lengths of the roller) up to 120 cm. that is, suitable for the broadest existing sheets. The length of the sheets to be operated with, is unlimited in principle, in practice generally 0.5 to 1.0 meters. The roller must be exactly cylindrical, but need not be finished better than normal turner's work, even ordinary drawn bars or tubes are sufficient. For instance the layer of thin soft rubber to be used need not be finished more accurately than for example the inner tube of a bicycle. By the peculiar action of the apparatus which is largely based on adhesion, the passing material (paper) adheres perfectly close; also in uneven places such as small holes, scratches etc. so that these do not influence the result unfavourably.

Example 1

Highly-absorbent, mat paper prepared with a solution of:—

1.8%	1-diaethylamino-4-diazoniumchlorostannate	90
1 %	gelatine	95
1 %	oxalic acid	
2 %	Gummi arabicum	reduction agents
2 %	glucose	
2 %	thiocarbamide (antioxygene according to Moureu)	100

is exposed under a transparent drawing and the print is led through the described apparatus with a speed of $1\frac{1}{2}$ meters per minute. In the trough is a solution of the following composition:

3 %	potassium carbonate	alkali	110
2.5 %	potassium hydroxide		
0.3 %	phloroglucinol	azodyestuff-com-	
0.3 %	resorcin	ponents	
10 %	secondary sodium phosphate (buffersalt)		
5 %	sodium thiosulphate	reduction	115
10 %	sodium citrate	agents.	

On leaving the apparatus a perfectly uniformly developed black image has been obtained, which is hardly moist and perfectly dry in a few minutes. If the apparatus is supplied with an extra drying device, the print is immediately perfectly dry. The speed of the apparatus can vary from 1-6 meters per minute circumferential speed of the roller.

On account of the larger quantity of developer that is taken up with high speed, in that case a developer is preferably used which is poorer in alkali and azodyestuff component but is rich in the other components.

Example 2

With the aid of the apparatus described, prints are developed exactly as in example 1 on highly-absorbent mat paper, prepared with a solution of:

1.8%	1-dimethylamino-3-methylbenzene-4-diazonium-chloro stannate	
3%	boric acid	
10	0.3% phloroglucinol	75
0.2%	resorcin	
1.3%	hydroxylaminesulphate	
8%	glucose	
4%	sodium citrate	
15	2% tartaric acid	80
3%	thiocarbamide	
0.1%	hydrochinon	
	reduction agents	
	antioxyggenes	
	and a developer containing:	
	15% sodium carbonate	
20	5% sodium thiosulphate	85
	and possibly, also, a quantity of salts, if the images should not emerge perfectly sharp.	
	Positive images are obtained which are hardly moist, and perfectly dry within a few minutes.	
25		90

Example 3

The operation is carried out with the described apparatus exactly as in examples 1 and 2 and with paper prepared with a solution of:

2%	1-diazo-2-oxynaphthalin-4-sulphonic acid	95
0.3%	phloroglucinol	
35	1.0% oxalic acid,	100

whereas a solution as in example 2 is used as developer.

What I claim is:—

1.	Apparatus for developing phototypes comprising a roller for applying a developing liquid to the surface of a sheet to be developed, means for supplying developing liquid to the surface of said roller, an elongated non-rotating device having a plurality of spaced toothed members for pressing the sheet against said roller, and means for mounting said device in operative relation with said roller so that said members bear against the sheet with a pressure sufficient to cause the sheet to follow part of the periphery of said roller in such manner that the developing liquid is spread upon the surface of the sheet to be developed in a thin even layer.	105
55	2. Apparatus for developing photo-types comprising a roller for applying a developing liquid to the surface of a sheet to be developed, means for supplying developing liquid to the surface of said roller, an elongated non-rotating device having a comb for pressing the sheet against said roller, and means for mounting said device in operative relation with said roller so that said comb bears against the sheet with a pressure sufficient to cause the sheet to follow part of the periphery of said roller in such manner that the	110

developing liquid is spread upon the surface of the sheet to be developed in a thin even layer.

In testimony whereof I affix my signature.
